CLAIM

The ornamental design for a charging case for wireless earphones, as shown and described.

DESCRIPTION

FIG. 1 is a top, front, left side perspective view of a charging case for wireless earphones, showing my new design in a closed configuration;

FIG. 2 is a top, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged top, rear, right side perspective view of the detail identified in FIG. 2; and,

FIG. 10 is a top, front, left side perspective view of the charging case for wireless earphones of FIG. 1, shown in an open state.

The broken lines in the drawings depict portions of the charging case for wireless earphones that form no part of the claimed design.

1 Claim, 10 Drawing Sheets
